UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed April 6, 1922. Serial No. 550,103.

To all whom it may concern:

Be it known that I, CARL D. BROWN, a citizen of the United States, and a resident of Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanism for looms whereby the filling in the shuttle is renewed from time to time without stopping the loom.

One of the objects of the present invention is to provide a feeler mechanism with 15 a feeler lock which will prevent the feeler from calling a change of filling until the filling in the shuttle has reached a predetermined degree of exhaustion. Various forms of feeler locks have heretofore been devised, but they have depended, in most cases, upon a measuring function of the feeler to determine the time at which the 20 feeler lock shall be tripped to free the feeler to its indicating movement. These various forms of feeler locks have been operated to release the feeler by a forward movement of the lock, and since the amount of forward movement has been dependent upon 25 the measured amount of filling in the shuttle, the feeler lock has not always accurately performed its unlocking function.

The present invention provides a feeler 30 lock which is mounted to be displaced in a direction longitudinally of the shuttle by the forward pressure of a surface carried by the lay, so that after such movement of the feeler locking device the feeler is freed 35 to perform its indicating function.

In the present instance of the invention the feeler mechanism is shown as provided 40 with a feeler of the inclined type which enters the shuttle on a detecting beat in a direction inclined to the longitudinal axis 45 of the shuttle, and a feeler lock under control of a controlling member which likewise enters the shuttle on its detecting beat and engages the filling, until when the filling 50 reaches a predetermined degree of exhaustion the controlling member is engaged by an exposed inclined surface carried by the lay to effect movement of the controlling

member longitudinally of the shuttle and 55 perforce trip the lock.

The various features of the invention and the combination of parts within the true scope thereof will best be understood by the following description and accompanying drawings which show one good practical 60 form of the invention.

In the drawings:

Fig. 1 is a perspective view of a feeler mechanism embodying the present invention.

Fig. 2 is a plan view showing the action of the feeler mechanism of the present invention when a working supply of filling is present in the shuttle on a detecting beat.

Fig. 3 is a similar view showing the action of the feeler mechanism when the filling is substantially exhausted on a detecting beat.

Fig. 4 is a detached detail showing the slide and locking shoulder for engaging the 75 lock.

The filling replenishing mechanism is not herein illustrated because the present invention is not concerned with the details thereof and it may be of usual character now 80 well understood in the art. Nor has it been deemed necessary to illustrate the details of the entire train of mechanism for effecting replenishment of filling when the feeler is moved longitudinally along the filling carrier or bobbin, such train of mechanism however may be of usual type such, for instance, as shown in the patent to Edward S. Stimpson, No. 1,309,226, July 8, 1919.

The feeler mechanism may be attached to 90 the loom frame by a bracket 1 to which the feeler stand 2 is adjustably secured by means of the bolt 3 and slot 4 formed in the feeler stand. The feeler 5 is shown as of the inclined type having a toothed or roughened 95 engaging end 6. At the front of the feeler stand 1 the feeler 5 passes through a rocking bearing 7 pivotally supported at 8 between a bracket 9 and the feeler stand. At its rear portion the feeler stand 2 has a bearing in 100 which is mounted a laterally movable slide through which the feeler extends. In the present instance the rear bearing is formed by the lugs or projections 10 between which is formed a guide way for the laterally mov- 105 able slide 11. The slide 11 has an opening

- 12 through which the feeler 5 extends, such opening 12 being of sufficient extent to permit the feeler to have a normal lateral movement therein as it is moved frontwardly on 5 a detecting beat when a working supply of filling is in the shuttle. The feeler slide is maintained in its guide way by a cap piece 13 which may be secured to the lugs or projections 10 by bolts or screws 14.
- 10 Between the front and rear bearings the feeler 5 carries a bridged piece 15 and between the bridged piece and the front bearing 7 is a spring 16 normally acting to move the feeler rearwardly into feeling position.
- 15 So far as described, the feeler mechanism, when of the inclined type, may be substantially as shown and described in the Stimpson patent hereinbefore mentioned.

The laterally movable slide 11 is provided 20 with a locking shoulder 17, shown in the present instance as formed on the end 18 of the slide. The slide 11 is connected by the transmitter 19 to the train of mechanism for effecting replenishment of the 25 filling.

Mounted on the feeler stand is the lock 20 which in the present instance is shown as pivoted on the rear portion of the feeler stand at 21 and carrying at its free end 30 portion a locking finger 22 which normally stands in obstructing relation to the locking shoulder 17 of the slide and holds the slide from lateral sliding movement. The lock 20 adjacent its pivotal portion is provided 35 with a sleeve or guide way 23 through which passes the lock controlling member 24. In the present instance the member 24 is provided with a slot 25 through which the pivot 21 of the feeler extends, the construction 40 being such that the lock controlling member 24 may move frontwardly without obstruction relative to the lock. The front end portion 26 of the lock controlling member has attached thereto a spring 27 the 45 rear end portion of which is secured to a lug 28 which may be conveniently provided with a series of holes 29 to permit adjustment of tension and direction of pull of spring 27. As indicated in Figs. 1, 2 and 50 3, the spring 27 normally acts upon the lock controlling member 24 to move it rearwardly and by its direction of pull likewise normally acts to move lock 20 into locking position. A stop or shoulder 30 may 55 if desired be formed upon the lock controlling member 24 to limit its rearward movement under the impulse of the spring 27.

If desired an adjustable stop 31 may be 60 mounted upon the cap 13 of the rear bearing to limit the movement of the locking arm 20 to its locking position under the action of the spring 27 and similarly if desired the lug 28 may be employed as an additional stop to limit the unlocking movement of the locking arm 20. The rear por-

tion of the lock controlling member 24 is downturned at 32 to bring its rear end portion into a substantially same horizontal plane as the rear end portion 6 of the feeler. In the present instance the rear or engaging 70 end portion of the member 24 is provided with a roller 33.

The front wall of the shuttle box is provided with an opening 34 and likewise the adjacent wall of the shuttle 35 is provided 75 with an opening 36 through which openings the feeler and lock controlling member may extend into the shuttle on a detecting beat and engage the filling or surface carried by 80 the shuttle.

In the present instance of the invention the shuttle 35 has the usual bobbin holding jaws 37 which engage the usual rings 38 formed on the head or large portion of the 85 bobbin 39.

The bobbin 39 has an inclined portion 40 which, if desired, may be stepped and when the shuttle is in the detecting box the inclined portion 40 of the bobbin is opposite 90 the rear or engaging end of the lock controlling member 24.

The bobbin or filling carrier 39 may have a reserve supply of filling or weft 41 wound thereon at either side of the inclined portion 40. In the present instance the reserve supply of filling is shown as wound 95 to the right of the inclined portion 40.

When a working supply of filling is present in the shuttle on a detecting beat both the feeler and the lock controlling member 100 24 enter the shuttle and engage the filling and are moved frontwardly by it. At such times no tendency is imparted to the lock controlling member to trip the lock so that the laterally movable slide 11 remains locked 105 and even though the feeler may tend to move longitudinally of the shuttle, the accomplishment of such movement is prevented by the locked slide. When however the filling reaches a predetermined degree 110 of exhaustion and the inclined portion 40 of the bobbin is exposed for engagement by the rear end of the lock controlling member, the forward pressure of the inclined portion 40 upon the lock controlling member 115 will cause it to be moved in a direction longitudinally of the shuttle and perchance trip the lock and free the feeler to its indicating movement. In such case, if the amount of

filling in the shuttle which is engaged by 120 the feeler is sufficient to prevent movement of the feeler longitudinally of the shuttle, the feeler will not partake of such movement even though unlocked, but when the reserve supply of filling is so far exhausted 125 as to be unable to hold the feeler from movement longitudinally of the shuttle due to forward pressure upon the feeler, the latter will move longitudinally of the shuttle and since at such time the laterally 130

movable slide 11 is unlocked the slide will be moved laterally by the feeler and replenishment of filling be effected.

From the construction described with reference to the form of the invention shown it will be noted that the lock controlling member 24 meets the cylindrical surface of the filling or bobbin in a direction normal to its surface, and when a supply of filling sufficient for working purposes protects the inclined portion 40 of the filling carrier or bobbin from engagement by the lock controlling member the latter will be moved directly forward without tendency of movement longitudinally of the shuttle, until when the inclined portion 40 of the bobbin is exposed for engagement by the lock controlling member, the frontward pressure upon the latter will effect its movement longitudinally of the shuttle. This construction is the preferred form or type because no injurious effect is exerted upon the filling by the engaging end of the lock controlling member but in some cases where the bobbin may not have an inclined surface for engagement by the lock controlling member, the latter may be placed in an inclined position. A reserve supply of filling also may be placed nearer the base portion or head of the bobbin in which case the feeler will act upon that portion of the bobbin towards the head or base thereof rather than in the opposite direction as shown.

What is claimed is:

35. 1. In a feeler mechanism for looms, the combination of a feeler mounted for movement towards and from the front of the loom and also in a direction longitudinally of the shuttle, a feeler lock which prevents replenishment of the filling in the shuttle until the filling is substantially exhausted, a bobbin engaging member which is moved in a direction longitudinally of the shuttle by the frontward pressure upon it when the filling is substantially exhausted on a detecting beat to trip the lock and free the feeler, and means actuated by movement of the feeler for effecting replenishment of filling.

50. 2. In a feeler mechanism for looms, the combination of a feeler, and a feeler lock controlling member both of which enter the shuttle on a detecting beat and engage the filling, a feeler lock controlled by said member, and a surface within the shuttle which is exposed for engagement by the feeler lock controlling member and acting by frontward pressure thereon to move the controlling member in a direction longitudinally of the shuttle when the filling has 55 reached a predetermined degree of exhaustion on a detecting beat to thereby trip the lock and free the feeler.

60. 3. In a feeler mechanism for looms, the combination of a feeler and a feeler lock controlling member both of which enter the

shuttle and engage the filling on a detecting beat when a working supply of filling is present in the shuttle, a bobbin carried by the shuttle having an inclined surface which is exposed for engagement by the feeler lock controlling member when the filling in the shuttle has been exhausted to a predetermined extent and acting by frontward pressure to move the said member in a direction longitudinally of the bobbin, and a feeler lock which is tripped by the controlling member when it is moved longitudinally of the shuttle.

4. A feeler mechanism for looms, comprising, in combination, a feeler, a feeler lock, both of which enter the shuttle on each detecting beat and a feeler lock controlling member mounted for displacement in a direction longitudinally along the filling carrier by the frontward pressure of the filling carrier upon it when the filling is substantially exhausted on a detecting beat, and connections between the feeler lock and controlling member for tripping the lock and freeing the feeler when the controlling member is displaced longitudinally of the shuttle on a detecting beat.

5. A feeler mechanism for looms, comprising, in combination, a feeler, a feeler lock, and a feeler lock controlling member having a rolling contact end for engagement with a surface within the shuttle and mounted for displacement in a direction longitudinally of the shuttle by the frontward pressure of a surface within the shuttle when the filling is substantially exhausted on a detecting beat, and connections between the feeler lock and controlling member for tripping the lock and freeing the feeler when the controlling member is displaced longitudinally of the shuttle on a detecting beat.

6. In a feeler mechanism for looms, the combination of a feeler supported to enter the shuttle in a direction inclined to the longitudinal axis of the shuttle, a laterally movable slide through which the feeler extends and which is given lateral sliding movement by the feeler when the feeler is moved along the filling carrier or bobbin on a detecting beat, connections with the slide for effecting replenishment of filling; a lock for holding the slide from lateral movement until the filling is substantially exhausted on a detecting beat, and a lock controlling member moved in a direction longitudinally of the shuttle by the frontward pressure upon it when the filling is substantially exhausted to free the slide for movement by the feeler.

7. In a feeler mechanism for looms, the combination of a feeler supported to enter the shuttle in a direction inclined to the longitudinal axis of the shuttle, a feeler lock, a feeler lock controlling member supported to enter the shuttle and engage the filling

on a detecting beat until the filling is substantially exhausted and then engage an inclined surface of the filling carrier and displaced in a direction longitudinally of the shuttle by the forward pressure upon it, and connections between the lock and controlling member for tripping the lock and freeing the feeler.

8. A feeler mechanism for looms, having in combination a feeler supported to enter the shuttle in a direction inclined to the longitudinal axis thereof on a detecting beat, a laterally movable slide through which the feeler extends, a lock for locking the slide from lateral movement, a lock controlling member supported to enter the shuttle on a detecting beat and engage the filling until the filling reaches a predetermined degree of exhaustion and then to engage and to be moved longitudinally along the filling carrier or bobbin by the forward pressure, and connections between the controlling member and lock for freeing the slide to lateral movement when the controlling member is moved longitudinally along the filling carrier or bobbin.

9. In a feeler mechanism for looms, the combination of a feeler supported to enter the shuttle in a direction inclined to the longitudinal axis of the shuttle on a detecting beat, a laterally movable slide through which the feeler extends, a lock having a locking finger for engaging the slide and holding it from lateral movement, and a lock controlling member connected to the lock and laterally displaced in a direction longitudinally of the shuttle by the forward

pressure upon it to trip the lock and free the slide when the filling is substantially exhausted on a detecting beat.

10. In a feeler mechanism for looms, the combination of a feeler, a feeler lock, and a feeler lock controlling member, connections between the feeler lock and controlling member which permits movement of the controlling member forwardly relative to the lock on each detecting beat, means normally acting to return the controlling member rearwardly when it has been displaced forwardly on the beat-up, and an inclined surface carried by the shuttle to cause the forward pressure against the controlling member to move it in a direction longitudinally of the shuttle when the filling has reached a predetermined degree of exhaustion and thereby trip the lock.

11. In a feeler mechanism for looms, the combination of a feeler mounted to be displaced in a direction longitudinally of the shuttle by the forward pressure upon it when the filling is substantially exhausted on a detecting beat, a lock for preventing premature movement of the feeler longitudinally of the shuttle, and a controller for the lock which engages an inclined surface on the filling carrier when the filling is substantially exhausted on a detecting beat and is itself laterally displaced by the forward pressure of the inclined surface to trip the lock.

In testimony whereof, I have signed my name to this specification,

CARL D. BROWN.
